UNITED STATES PATENT OFFICE.

ROBERT L. McELROY, OF NEW YORK, N. Y., AND JOHN E. SHEPHERD, OF UNIVERSITY, VIRGINIA.

AUTOMATIC FIRE-EXTINGUISHING SYSTEM.

1,264,196.

Specification of Letters Patent. Patented Apr. 30, 1918.

Application filed March 12, 1917. Serial No. 154,110.

To all whom it may concern:

Be it known that we, ROBERT L. McELROY, a citizen of the United States, residing at New York, in the county of New York and State of New York, and JOHN E. SHEPHERD, a citizen of the United States, residing at University, in the county of Albemarle and State of Virginia, have invented certain new and useful Improvements in Automatic Fire-Extinguishing Systems, of which the following is a specification.

The main and primary objects of our invention herein shown, described and claimed, is to provide an automatic fire extinguishing system, and apparatus of exceedingly cheap and simple form of construction, having little liability to get out of order, and extremely sensitive to rapid rises of temperature occasioned by fire.

To such ends, our invention comprises broadly and in substance a sprinkling member or members, adapted to emit and discharge fire extinguishing fluidal material upon the fire zone, when electric switch mechanism is automatically closed by the heat from the fire zone, so as to increase the pressure in the receptacle or receptacles holding the fluidal fire extinguishing material, by the heating of an electric heater located therein; and a second and auxiliary heating means, such as a steam-coil, for also supplying heat to such fluidal fire extinguishing material, to the point of expulsion of the same, which auxiliary heating device is also put into operation by the heat in the fire zone by the actuation of suitable thermostatic-devices, all the mechanisms being so arranged and interconnected that liability of failure of the apparatus to discharge the fire extinguishing fluidal material upon the fire zone, will be reduced to a minimum, all as hereinafter more fully set forth.

While we have shown herein an air filled thermostatic device for putting the apparatus into action by the expansion of the entrapped air therein; any suitable thermostatic device that is sufficiently sensitive, but not so much so as to be liable to actuation by increase of temperature from other causes than fire in the immediate vicinity, may be used. Also other fluids than atmospheric air, or even expansible or volatilizable fluids

may be used with equal effect, and as used herein, in the description and claims, we intend the term fluid and its correlatives to cover all expansible fluids gaseous or liquid.

Said invention is fully shown and described in the following specification, of which the accompanying drawings form a part, wherein similar letters or numerals of reference designate like or equivalent parts, wherever found throughout the several views, and in which:—

Figure 1, is a diagrammatic top plan view of a room or apartment provided with our improved automatic fire extinguishing apparatus; the receptacle for holding the fire extinguishing fluid being located exterior to such apartment;

Fig. 2, is a diagrammatic view on an enlarged scale of the electric heating coil, electric supply source and automatic switch closing mechanism; and

Fig. 3, is a like view showing a modified form of such switch, and switch closing mechanism.

Fig. 4, is a somewhat modified form of construction from that shown in Figs. 1 to 3, partially in section, showing additional means for heating the fluidal material, both within the receptacle and without; and

Fig. 5, is a view similar to Fig. 4, showing an addition to the structure shown in such Fig. 4, whereby the remaining contents of the receptacle will be forcibly expelled by steam pressure, when the same has been nearly emptied.

Referring to the drawings;

The reference numeral A designates the wall of the room or apartment; and B the receptacle or tank containing the fire extinguishing fluid, which may be any fluid capable of quickly and rapidly extinguishing the fire; but we prefer to use therefor carbon tetrachlorid. The reference letter C designates a source of electrical energy, usually a battery, having an electrical circuit composed of the wires 1, 2 and 3, in which circuit is included an electric heating-coil or heater D, of any desired form of construction, which is located in the receptacle B, so that when energized it will heat the fire extinguishing fluid therein.

Located in the apartment A, is the appa-

ratus for discharging therein the fire extinguishing fluid contained in the receptacle B, upon the occurrence of a fire therein; and such apparatus may be of many and various forms, but a cheap and efficient one consists of an arrangement of piping supported adjacent to the ceiling of the room or apartment, comprising a header-pipe 4, having connected thereto a plurality of outlet pipes 5, usually two or more in number, as shown, according to the size of the room or apartment to be protected thereby. Such outlet-pipes 5 are provided with a plurality of outlet perforations 6, usually and preferably formed in and through the upper walls thereof, so that the fire extinguishing fluid issuing from such orifices will be directed against the ceiling of the room and thus be spattered thoroughly throughout the same.

The outlet orifices 6, in order to prevent dust, etc., from entering the pipe therethrough, are usually and preferably plugged with some low fusible material, such as soft paraffin wax or the like.

Located adjacent to such outlet-pipes 5, and usually surrounding the same in the form of a rectangle, as shown, is the pipe 8, in communication, at its outer end, with a diaphragm-box 9, having secured in its outer face in any desired manner the diaphragm 10, having secured to the central portion of its face the electric contact-disk 11, which when such diaphragm is forced outward by increase of the air-pressure in the pipe will contact with the electric contact-plate 12, so as to close the electric heating-coil or heater circuit. For the purpose of preventing ordinary changes of temperature affecting the diaphragm, the pipe 8 is usually provided with a very small relief perforation 13, outside of the apartment A, whereby actuation of the diaphragm 10, is prevented except upon the quick expansion of the air by a fire within the apartment.

The header-pipe 4, is connected with the bottom of the tank B by way of the pipe 14, for purposes of repair preferably provided with a stop-cock or valve 15; which pipe 14 communicates with the tank or receptacle B at or adjacent to the bottom by way of the pipe 16; and usually and preferably coiled around the pipe 14 is a heating-coil 17, connected at one end by a wire 3' with the circuit wire 3, and at the other by the wire 2' with the circuit wire 2, so that the same will be energized and heated simultaneously with the coil D, upon the closing of the electric circuit. In the modified form of switch shown in Fig. 3, the contact member 11', is normally in contact with a knife 11 pivoted thereto, which is usually provided with an upwardly bowed central-portion 18, which when the switch

is in the open position shown in full lines, 65 is normally in contact with the diaphragm 10; and upon the expansion of the entrapped air in the pipe 7, upon the occasion of a fire, and the consequent throwing of such diaphragm into the position shown in dotted-lines, in such Fig. 3 as shown at 10', such knife of the switch will be thrown into the circuit closing position shown in dotted lines, so as to close the circuit, and energize the heating-coils, and continue to energize them, until released by hand.

While we have shown our improved fire extinguishing system, as adapted only to one room or apartment, it is self-evident that the reservoir B, may be connected with several such apartments, and that upon the occurrence of a fire in any one apartment, the fire extinguishing fluid will escape only in the apartment where the fire exists.

Upon the occurrence of a fire the expansion of the air trapped in the pipe 8, closing the electric-circuit will cause high heating of the heating-coil D, which will immediately bring about a quick and rapid expansion of the carbon tetra-chlorid or other extinguishing fluid in the receptacle B, and the vapor generated rising to the top of the receptacle will force the liquid into the apartment by way of the pipes 16, 14, 4 and 5 and out through the orifices 6, 95 upon the fire-zone. Carbon tetra-chlorid is the liquid we prefer to use, for the reason that in addition to its great fire extinguishing capability, it volatilizes at a comparatively low temperature, that is about 171° F, or 77° C.

One of the advantages of our improved fire extinguishing system and apparatus herein shown and described consists in the fact that immediately upon the extinguishment of the fire, and consequent cooling and contraction of the air in the pipe 8, when the form of switch shown in Fig. 2, is used, this will automatically break the electric circuit between 11 and 12, and the heating 110 action of the coils will at once cease and consequently the flow of the extinguishing fluid will also be at once stopped. But for some purposes and under certain conditions, the form of switch shown in Fig. 3, which 115 will remain closed when once thrown into the circuit closing position, until thrown open by hand may be used, in which case the tank B will of course be completely emptied.

It will be seen that another advantage of our improved form of apparatus lies in the fact that as the sprinkling pipes 5 contain none of the liquid; the same is out of contact with the atmosphere and cannot 125 therefore wastefully volatilize into the atmosphere, and that it is only when a fire occurs that the electric circuit is closed and

5 by the heating of the carbon tetra-chlorid or other fire-extinguishing fluid that the same is by its own expansion passed into the pipes 5 and transmitted to sprinkle upon the fire-zone.

10 In the modified form of construction shown in Fig. 4, mounted upon the pipes 5, between the sprinkler orifices 6, are a plurality of flanges or heat transmitting 15 rings 20, usually of some highly heat conducting material such as copper, etc., by which the heat of the fire-zone will be transmitted through the pipe-wall to the fire-extinguishing fluid within the same. And in this form, located in the fire extinguishing fluid receptacle B, below the electric heating coil D, is a steam heating coil E, having no connection with the receptacle B, connected with a suitable steam supply-source 20 (not shown) by a steam inlet pipe 21. And such inlet pipe 21 is in connection with the inlet pipe 22 of the steam heating coil E; which coil E has an outlet pipe 22'. The pipe 21 is provided with a normally closed 25 stop-cock 37 actuated by a vibrating lever 23, adapted to be retracted into the valve opening position (shown in dotted lines in Fig. 5) by a coil-spring 24 secured at the upper end to such valve lever 23 and at the 30 other and lower end to a bracket-piece 25 formed integral with or secured to the pipe-elbow 26.

35 And the valve-lever 23 is normally maintained in the horizontal and valve closing position shown in full lines in Fig. 4, by contact at its outer end with a horizontal solenoid plunger 27, retracted by the energizing of the solenoid coil 28, so as to release such valve lever 23, upon such coil 40 28 being energized by the current from the battery C through the wires 29 and 30, as indicated, upon the closing of the electric contacts 11 and 12. By which action the carbon tetra-chlorid or other fire extinguishing fluidal material in the receptacle B, will 45 be highly heated both by the electric heating coil D, and by the steam coil E, and expanded and vaporized so as to generate sufficient pressure in the receptacle to force 50 such fire extinguishing fluidal material out of the receptacle by way of the various pipes, and the orifices 6 of the pipes 5, such material being additionally heated by the energizing of the heating coil 17 and 55 the pipe 14, and the heat transmitted to the pipe 5 from the fire zone, especially by the heating rings 20.

60 And it will be seen that by thus having two sources of heat for heating the fire extinguishing fluidal material to the point of expansion, namely, one electric and one steam, the liability of failure of the device to operate and expel the fluidal fire extinguishing fluidal material upon the fire zone at

the critical movement is reduced to an absolute minimum.

65 Fig. 5 shows a structure differing in no particular way from that shown in Fig. 4, save only that within the receptacle B, between the steam coil and the outlet pipe 22' thereof, adjacent to the bottom of the tank, is located a float-valve 32, actuated by a float 33, carried upon the end of a vibrating float-lever 34, pivoted at 35, and when the receptacle is more than one third full, normally keeping the valve rod 32' of the valve 70 32 in the horizontal valve closing position indicated in full lines; such valve being kept in such normally closed position by a suitable spring (not shown) usually located 75 within the valve-casing, and upon the level of the liquid in the receptacle falling below the horizontal normal position of the float-valve lever 34 shown in full lines in Fig. 5, such valve 32 will be opened so as to allow 80 live steam to escape into the receptacle as indicated by the arrows, whereby all the carbon tetra-chlorid will under the pressure of such steam, by the falling of the float as shown in dotted lines, be forced out of the 85 receptacle upon the fire-zone.

90 While in Figs. 4 and 5 we have shown the heating coils adjacent to the top of the receptacle D, usually and preferably such coils may be located at the bottom so as to heat 95 the carbon tetra-chlorid, etc., even though but a small portion remains therein, but as that portion of the drawings showing such coils are diagrammatic, we have not deemed it essential to so show the same in such lower 100 position.

Many modifications and changes of construction other than those shown and described herein may be made without departing from the scope of our invention, and we 105 do not intend to limit ourselves to the exact construction or arrangement of any of the several parts of our said invention herein shown.

We claim:

110 1. An automatic fire-extinguishing system, comprising a sprinkling apparatus adapted to discharge a fire extinguishing fluid upon the fire-zone; a receptacle adapted to contain a fire extinguishing fluid in communication with the sprinkler; means for heating the fire extinguishing fluid so that its own expansion will force it into and out of the sprinkler upon the fire-zone; and a thermostatic device located adjacent to the 115 sprinkler adapted to put the liquid heating apparatus into action upon the temperature reaching a predetermined high point.

120 2. An automatic fire-extinguishing system, comprising a sprinkling apparatus adapted to discharge a fire extinguishing fluid upon the fire-zone; a receptacle adapted to contain a fire extinguishing fluid in

communication with the sprinkler; means for heating the fire extinguishing fluid so that its own expansion will force it into and out of the sprinkler upon the fire-zone; and a thermostatic device located adjacent to the sprinkler adapted to put the liquid heating apparatus into action upon the temperature reaching a predetermined high point, the sprinkler system being normally and until the actuation of the heating device unfilled with the fire extinguishing fluid.

3. An automatic fire-extinguishing system, comprising a sprinkling apparatus adapted to discharge a fire extinguishing fluid upon the fire-zone; a receptacle adapted to contain a fire extinguishing fluid in communication with the sprinkler; means for heating the fire extinguishing fluid so that its own expansion will force it into and out of the sprinklers upon the fire-zone; and a fluid thermostatic device located adjacent to the sprinkler adapted to put the liquid heating apparatus into action upon the temperature reaching a predetermined high point, by the expansion of the fluid therein.

4. An automatic fire-extinguishing system, comprising a sprinkling apparatus adapted to discharge a fire extinguishing fluid upon the fire-zone; a receptacle adapted to contain a fire extinguishing fluid in communication with the sprinkler; means for electrically heating the fire extinguishing fluid so that its own expansion will force it into and out of the sprinkler upon the fire-zone; and a fluid thermostatic device located adjacent to the sprinkler adapted to set the liquid heating apparatus into action upon the temperature reaching a predetermined high-point, by the expansion of the fluid in the thermostatic device.

5. An automatic fire-extinguishing system, comprising a sprinkling apparatus adapted to discharge a fire extinguishing fluid upon the fire-zone; a receptacle adapted to contain a fire extinguishing fluid in communication with the sprinkler; means for electrically heating the fire extinguishing fluid so that its own expansion will force it into and out of the sprinkler upon the fire-zone; and an atmospheric thermostatic device located adjacent to the sprinkler adapted to set the liquid heating apparatus into action upon the temperature reaching a predetermined high-point, by the expansion of the air in the thermostatic device by closing the electric circuit.

6. An automatic fire-extinguishing system, comprising a sprinkling apparatus adapted to discharge a fire extinguishing fluid upon the fire-zone; a receptacle adapted to contain a fire extinguishing fluid in communication with the sprinkler; means for electrically heating the fire extinguishing fluid so that its own expansion will force

it into and out of the sprinkler upon the fire-zone; and a fluid thermostatic device located adjacent to the sprinkler adapted to set the liquid heating apparatus into action upon the temperature reaching a predetermined high-point, by the expansion of the fluid in the thermostatic device closing the electric circuit, the sprinkler system itself being normally and until the actuation of the heating device filled only with air.

7. An automatic fire-extinguishing system, comprising a sprinkling apparatus comprising a pipe arranged adjacent to the roof of the apartment to be protected, having perforations in the upper wall portion, adapted to discharge a fire extinguishing fluid upon the fire-zone; a receptacle adapted to contain a fire extinguishing fluid in communication with the sprinkler; means for heating the fire extinguishing fluid so that its own expansion will force it into and out of the sprinkler upon the fire-zone; and a thermostatic device located adjacent to the sprinkler adapted to put the liquid heating apparatus into action upon the temperature reaching a predetermined abnormally high point.

8. An automatic fire-extinguishing system, comprising a sprinkling apparatus comprising a pipe arranged adjacent to the roof of the apartment to be protected, having perforations in the upper wall portion normally closed by an easily fusible material, adapted to discharge a fire extinguishing fluid upon the fire-zone; a receptacle adapted to contain a fire extinguishing fluid in communication with the sprinkler; means for heating the fire extinguishing fluid so that its own expansion will force it into and out of the sprinkler upon the fire-zone; and a thermostatic device located adjacent to the sprinkler adapted to put the liquid heating apparatus into action upon the temperature reaching a predetermined abnormally high point.

9. In a device of the class described, a sprinkler adapted to discharge a fire extinguishing fluid upon the fire-zone; a receptacle adapted to contain a fire extinguishing fluid in communication with the sprinkler; an electric heater adapted to heat the fluid in such receptacle upon the closing of the electric circuit; a source of electric energy forming part of such electric circuit; a fluid thermostatic device arranged adjacent to the sprinkler; and a normally broken electrical contact, closed by the action of the thermostat upon the temperature adjacent to the sprinkler reaching a predetermined abnormally high point, and the consequent expansion of the fluid in the thermostatic device.

10. In a device of the class described, a sprinkler adapted to discharge a fire ex-

- tinguishing fluid upon the fire-zone; a receptacle adapted to contain a fire extinguishing fluid in communication with the sprinkler; an electric heater adapted to heat the fluid in such receptacle upon the closing of the electric circuit; a source of electric energy forming part of such electric circuit; a fluid thermostatic device arranged adjacent to the sprinkler; and a normally broken electrical contact, closed by the action of the thermostatic device upon the temperature adjacent to the sprinkler reaching a predetermined abnormally high point, and the consequent expansion of the fluid in the thermostatic device; the thermostatic device being provided with a relief orifice for permitting gradual escape of the entrapped fluid during slight rises in temperature caused by normal conditions.
11. In a device of the class described, a sprinkler adapted to discharge a fire extinguishing fluid upon the fire-zone; a closed receptacle adapted to contain a fire extinguishing fluid in communication with the sprinkler; a steam supply-pipe; a steam heating-coil located in the receptacle in communication with the steam supply pipe; a normally closed automatically opened valve located in the pipe-line; and means for automatically releasing such valve upon the temperature reaching a predetermined high-point.
12. In a device of the class described, a sprinkler adapted to discharge a fire extinguishing fluid upon the fire zone; a closed receptacle adapted to contain a fire-extinguishing fluid in communication with the sprinkler; an electric-heater located in the receptacle adapted to heat the fluid in such receptacle upon the closing of the electric circuit of the heater; a source of electric energy included in such circuit; a thermostatic device arranged adjacent to the sprinkler, a normally broken electrical contact, closed by the action of the thermostatic device upon the temperature adjacent to the sprinkler reaching an abnormal predetermined high point; a steam-supply pipe; a steam heating-coil located in the receptacle; in communication with the steam supply-pipe; a normally closed automatically opened valve located in the pipe-line; and means for automatically releasing such valve upon the temperature reaching a predetermined high-point.
13. In a device of the class described, a sprinkler adapted to discharge a fire extinguishing fluid upon the fire zone; a closed receptacle adapted to contain a fire extinguishing fluid in communication with the sprinkler; a steam supply-pipe; a steam heating-coil located in the receptacle in communication with the steam supply-pipe; a normally closed float-valve connected with
- the steam-coal, adapted to automatically open upon the falling of the float so as to admit steam to the receptacle; a normally closed automatically opened valve located in the pipe-line; and means for automatically releasing such valve upon the temperature reaching a predetermined high-point.
14. In a device of the class described, a sprinkler adapted to discharge a fire extinguishing fluid upon the fire zone; a closed receptacle adapted to contain a fire-extinguishing fluid in communication with the sprinkler; an electric-heater located in the receptacle adapted to heat the fluid in such receptacle upon the closing of the electric circuit of the heater; a source of electric energy included in such circuit; a thermostatic device arranged adjacent to the sprinkler; a normally broken electrical contact, closed by the action of the thermostatic device upon the temperature adjacent to the sprinkler reaching an abnormal predetermined high point; a steam supply-pipe; a steam heating-coil located in the receptacle, in communication with the steam supply-pipe; a normally closed float valve connected with the steam-coil, adapted to automatically open upon the falling of the float so as to admit steam to the receptacle; a normally closed automatically opened valve located in the pipe line; and means for automatically releasing such valve upon the temperature reaching a predetermined high-point.
15. In a device of the class described, a sprinkler adapted to discharge a fire extinguishing fluid upon the fire zone; a closed receptacle adapted to contain a fire-extinguishing fluid in communication with the sprinkler; an electric-heater located in the receptacle adapted to heat the fluid in such receptacle upon the closing of the electric circuit of the heater; a source of electric energy included in such circuit; a subsidiary electric heater coil superposed upon the sprinkler feed-pipe outside of the receptacle, energized simultaneously with the heater in the receptacle; a thermostatic device arranged adjacent to the sprinkler; a normally broken electrical contact, closed by the action of the thermostatic device upon the temperature adjacent to the sprinkler reaching an abnormal predetermined high point; a steam supply-pipe; a steam heating-coil located in the receptacle in communication with the steam supply-pipe; a normally closed automatically opened valve located in the pipe line; and means for automatically releasing such valve upon the temperature reaching a predetermined high-point.
16. In a device of the class described; a closed receptacle adapted to contain a fluidal fire-extinguishing material; a heater located

within the receptacle; means for heating the heater; a thermostatic device automatically putting the heating means into operation upon the temperature reaching an abnormally high point; a sprinkler-pipe system in communication with the receptacle; and a subsidiary heater heating the pipe-system actuated simultaneously with the receptacle.

17. In a device of the class described; a closed receptacle adapted to contain a fluidal fire-extinguishing material; a heater located within the receptacle; means for heating the heater; a thermostatic device automatically putting the heating means into operation upon the temperature reaching an abnormally high point; a sprinkler pipe-system in communication with the receptacle; a subsidiary heater heating the pipe-system actuated simultaneously with the heater in the receptacle; and heat-conducting flanges or members carried by the sprinkler pipes adapted to conduct the heat of the fire-zone to such pipes and through them to the fire extinguishing fluid therein.

18. In a device of the class described, a sprinkler adapted to discharge a fire extinguishing fluid upon the fire zone; a closed receptacle adapted to contain a fire extinguishing fluid in communication with the sprinkler; an electro-heater located in the

receptacle adapted to heat the fluid in such receptacle upon the closing of the electric circuit of the heater; a source of electric energy included in such circuit; a subsidiary electric heater coil superposed upon the sprinkler feed-pipe outside of the receptacle, energized simultaneously with the heater in the receptacle; a fluid thermostatic device arranged adjacent to the sprinkler; a normally broken electrical contact, closed by the action of the thermostatic device upon the temperature adjacent to the sprinkler reaching an abnormal predetermined high point; a steam supply-pipe; a steam heating-coil located in the receptacle in communication with the steam supply-pipe; a normally closed automatically opened valve located in the pipe line; and means for automatically releasing such valve upon the temperature reaching a predetermined high-point; the thermostatic device being provided with a relief orifice for permitting gradual escape of the entrapped fluid during slight rises in temperature caused by normal conditions.
